UNITED STATES PATENT OFFICE.

FRED SEAMAN SHERMAN, OF CAMBRIDGE, MASSACHUSETTS, ASSIGNOR TO UNITED SHOE MACHINERY CORPORATION, OF PATERSON, NEW JERSEY, A CORPORATION OF NEW JERSEY.

DEVICE FOR LOCATING BOARDS ON BOOK COVERS.

Application filed July 11, 1927. Serial No. 204,904.

This invention relates a device for use in locating one blank of sheet material upon another and is herein illustrated as embodied in a device for use in locating the boards upon 5 the covers of cases of books.

The case of a book commonly comprises a cover of fabric, leather or imitation leather and two boards, over certain margins of which the cover is folded. In the manufacture of such cases two previously cemented boards are placed upon a cover with their outer edges spaced the desired distance from the edges of the cover to provide for the folding of the cover and with their inner edges 15 spaced apart a distance approximately equal to the thickness of the book for which the case is being made. The majority of cases of books have square corners and thick, stiff boards, such cases being commonly made in 20 large quantities on machines which automatically place the boards on the cover, fold the margin of the cover over the boards and deliver the completed cases. There are, however, a large number of book cases, such, for 25 example, as those having flexible boards and those having round corners, in the manufacture of which the boards are placed by hand upon the covers preparatory to folding the covers by hand or machine, since bookcases of 30 these kinds cannot be manufactured on the automatic machines referred to above. Commonly, the procedure of locating the boards by hand has been to place a cover upon a table, to place upon the cover a gage in the 35 form of a T square the width of the stem of which is equal to the desired distance between the boards and finally to place the previously cemented boards one on each side of the stem of the T with their upper edges in engagement with the top of the T, this procedure 40 requiring considerable skill on the part of the operator and being comparatively slow.

According to one feature of the present invention, there is provided a support for a 45 stack of blanks such as covers, a gage for smaller pieces such as the boards, and means for holding the gage in proper position on the top of the stack. In the illustrated device, the edges of the stack of covers are kept in 50 alignment by the walls of a magazine of which the support forms the base, and the walls are suspended from the top of the stack by an end gage which extends across the stack along the rear edge thereof, there being provided

side gages which are pivoted upon the end 55 gage and like it rest upon the top of the stack, treadle-controlled means being provided for raising the gages, and with them the walls of the magazine when desired. With this construction, the operator places the previously 60 cemented boards upon the topmost cover of the stack in contact with the end and side gages, presses the boards into place, depresses the treadle to lift the gages, pulls the cover with the boards attached to it from the stack 65 and releases the treadle, whereupon the gages descend upon the then topmost cover in position to facilitate the location of the next pair of boards. Thus the boards may be rapidly 70 and accurately placed.

It is desirable that the device be capable of use with covers of different sizes. According to another feature of the invention, the walls of the magazine are adjustable to provide for larger and smaller sizes of covers. 75 In the illustrated construction the walls are mounted upon a carrier and are adjustable in two directions on the carrier.

These and other features of the invention including certain details of construction and 80 combinations of parts will be described as embodied in an illustrative device and pointed out in the appended claims.

Referring now to the accompanying drawings, 85

Fig. 1 is a perspective of a device in which the present invention is embodied, and

Fig. 2 is a plan view partly in section.

The device comprises a base 3 which supports an upright square standard 5. Mounted upon the top of the standard is a support 7 for a stack of covers 100 of thin, flexible sheet material. The support 7 forms the base of a skeleton magazine. The front wall of the magazine is made up of two upright 90 flat bars 9, 11; the rear wall, of the two flat bars 13, 15; the right-hand wall, of the two flat bars 17, 19; and the left-hand wall of the two flat bars 21, 23. These bars are arranged in four pairs adjacent to the four corners of the support 7, the two members of each pair being integral with each other.

The bars 9 and 17 are connected near their upper ends by a right-angled portion 25 and at their lower ends by a right-angled portion 27; and the bars 11 and 23 are similarly connected. The bar 9 has at its base a horizontal extension 29 provided with a slot 31; and the

bar 11 has a similar extension 33, provided with a similar slot (not shown). The extensions 29 and 33 overlap each other and their slots are in register. These extensions are 5 horizontally slideable in a guideway in a member 35 and are clamped to said member by a headed bolt the stem of which passes through the slots in the extensions 29, 33, through a hole in the member 35 and has a thumb-nut 37 threaded upon its outer end. The member 10 35 is horizontally slideable upon a carrier in the form of a bar 39 having in one end thereof a slot 41. A cap screw 43 has its stem extending through the slot and threaded into the member 35. With this construction, when 15 the thumb-nut 37 has been loosened, the distance between the upright bars 17 and 23 may be varied to provide for covers of different widths; and when the cap screw 43 has been loosened, the bars 9 and 11 may be moved 20 forward or back to provide for covers of different lengths. The two pairs of upright bars 13, 19 and 15, 21 are mounted upon a member 53, which corresponds to the member 25 35, said member 53, like the member 35, being adjustably mounted upon the carrier 39. An inspection of Fig. 1 will show that when the thumb-nut 45 (which corresponds to the thumb-nut 37) has been loosened, an adjustment 30 may be made for wider or narrower covers; and that when the cap screw 47 which corresponds to the cap screw 43 has been loosened, an adjustment may be made for longer or shorter covers. It will be understood that 35 supports 7 of different sizes may be provided for covers differing in size, these supports being removably fastened to the top of the standard 5 by a screw 49.

The carrier bar 39 is conveniently made in 40 two parts with a split hub. This split hub has a square hole to receive the square standard 5, and its two parts are held together by screws, one of which is shown at 51. The carrier is thus slideable upon the standard 5; and 45 is suspended from the top of the stack of covers in the following manner. The member 53, at the rear of the device, which corresponds to the member 35 at the front thereof, has integral with it a bracket 55 which extends first upwardly and then horizontally. 50 Adjustably fastened upon the horizontal portion of the bracket 55, by a screw 56 is the short stem of a flat bar 57, the screw passing through a slot 59 formed in the stem. This bar 57 rests upon the top of the stack of covers and its front edge serves as a gage for the 55 ends of the boards 200. Gages 61, 63 for the sides of the boards are pivoted respectively at 65, 67 to the outer ends of arms 69, 71, the 60 inner ends of said arms having hubs which are adjustably fastened by set screws 73, 75 to a rock-shaft 77. This rock-shaft is rotatable in lugs 79 integral with the gage bar 57 and is held from longitudinal movement by collars 81.

In the operation of the device the covers, after the boards have been placed upon them and the gages slightly raised, are pulled one by one from the top of the stack over the front wall of the magazine, said front wall being 70 made up of the two upright bars 9 and 11. In order to facilitate the removal of the topmost cover from the stack, the tops of the bars 9, 11 are located at about the level of the under surface of the bar 57,—that is, the tops 75 of these bars are substantially flush with the top of the stack. In order to lift the carrier 39, and with it the walls of the magazine and the gages for the boards, when a cover is to be pulled from the top of the stack or when 80 a new stack of covers is to be placed upon the support 7, a lever 81, pivoted near its middle at 83 to a post rising from the base of the machine, has its inner end extending beneath the hub of the carrier 39, its outer end being 85 connected with the upper end of a treadle rod 82 to the lower end of which a treadle (not shown) is connected.

The side gages 61 and 63 are raised when the treadle is depressed by reason of bars 85, 90 87 fast respectively to the gages. The bar 85 rests upon a support in the form of a bar 89 adjustably fastened in angular position to the upright bar 17 of the magazine by a screw 91. The bar 87 rests upon a similar support 95 93 carried by the upright bar 23 of the magazine. The supports 89 and 93 are adjusted into such positions that the side gages 61, 63 normally rest lightly upon the top of the stack of covers 100.

Assuming that a stack of covers has been placed upon the support 7, the operation of the device is as follows:

Two boards, which have been properly cemented, are placed upon the topmost cover in the positions shown in the drawings with their upper edges as viewed in Fig. 2 in contact with the gage 57 and their outer side edges in contact respectively with the side gages 61, 63, and are pressed against the 110 cover. Commonly the boards each have a stripe of cement on their under faces extending along their adjacent margins, in which case the operator merely draws his forefingers along said adjacent margins on the upper 115 sides of the boards. The treadle is then depressed just enough to raise the gages slightly and take the weight of the gages and the parts associated with them from off the stack. The topmost cover is then seized, preferably 120 at two points in its near end as viewed in Fig. 1, and pulled from the stack over the tops of the bars 9, 11. The treadle is then released whereupon the carrier, with all its supported parts, descends until the gages rest upon the 125 then topmost cover of the stack, whereupon the operation described above may be repeated.

Although the invention has been set forth as embodied in a particular device for use 130

with a particular kind of work, it should be understood that the invention is not limited in the scope of its application to the particular device nor to the particular kind of work 5 which has been shown and described.

Having thus described my invention, what I claim as new and desire to secure by Letters Patent of the United States is:—

1. A device of the class described having, 10 in combination, a support for a stack of blanks, a gage, and means for holding the gage in proper position upon the top of the stack.

2. A device of the class described having, 15 in combination, a support for a stack of blanks, a gage for facilitating the locating of other blanks upon the topmost blank of the stack and means for holding the gage in position.

20 3. A device for use in locating smaller blanks upon larger blanks having, in combination, a support for a stack of the larger blanks and a gage for the smaller blanks adapted to rest upon the top of the stack and 25 to move down into engagement with the next lower blank when the topmost blank is removed.

4. A device for use in locating smaller blanks upon larger blanks having, in combination, a support for a stack of the larger 30 blanks and gages for engaging two edges of the smaller blanks, said gages being adapted to rest upon the top of the stack and to move down into engagement with the next lower 35 blank when the topmost blank is removed.

5. A device for use in locating smaller blanks upon larger blanks having, in combination, a support for a stack of the larger blanks, a gage for engaging corresponding 40 edges of the smaller blanks, said gage being adapted to rest upon the top of the stack, and two gages for engaging other edges of the smaller blanks, the last two gages being mounted upon the first gage and like it adapted 45 to rest upon the top of the stack.

6. A device for use in locating smaller blanks upon larger blanks having in combination a support for a stack of the larger blanks, a gage for the smaller blanks resting 50 upon the topmost blank of the stack, and operator-controlled means for raising the gage to permit the topmost blank to be withdrawn.

7. A device of the class described having, in 55 combination, a support for a stack of blanks, means for maintaining the edges of the blanks in alinement, and a gage resting upon the topmost blank and adapted to engage the next lower blank when the blank upon which it rests is removed.

8. A device of the class described having, 60 in combination, a support for a stack of blanks, a wall for engaging a side of the stack, and means for suspending the wall from the top of the stack whereby the wall

moves down as blanks are removed from the top of the stack.

9. A device of the class described having, 70 in combination, a support for a stack of blank material, a wall for engaging a side of the stack, the top of the wall being substantially flush with the top of the stack, and means for suspending the wall from the top of the stack whereby the wall moves down as pieces are removed from the top 75 of the stack.

10. A device of the class described having, 80 in combination, a magazine for a stack of blanks comprising a support for the bottom of the stack and walls for engaging the sides 85 of the stack, and means for suspending the walls from the top of the stack whereby the position of the walls varies with the height of the stack.

11. A device of the class described having, 85 in combination, a magazine for a stack of blanks comprising a support for the bottom of the stack and walls for engaging the sides 90 of the stack, and means for suspending the walls from the top of the stack whereby the position of the walls varies with the height 95 of the stack, the top of one of said walls being substantially flush with the top of the stack.

12. A device of the class described having, 95 in combination, a magazine for a stack of blanks comprising a support for the bottom of the stack and walls for engaging the sides 100 of the stack, and means for suspending the walls from the top of the stack whereby the position of the walls varies with the height 105 of the stack, the walls being adjustable to provide for blanks of different sizes.

13. A device of the class described having, 110 in combination, a support for a stack of blanks, a wall for engaging a side of the stack, a carrier for the wall and means for mounting the carrier for sliding movement in a path perpendicular to the plane of the blank support.

14. A device of the class described having, 115 in combination, a support for a stack of blanks, a wall for engaging a side of the stack, a carrier for the wall, means for mounting the carrier for sliding movement in a path 120 perpendicular to the plane of the blank support and means mounted upon the carrier for engaging the top of the stack.

15. A device of the class described having, 125 in combination, a support for a stack of blanks, a standard upon which the support is mounted, a carrier slideable upon the standard, walls mounted upon the carrier and means for suspending the carrier from the top of the stack.

16. A device of the class described having, 130 in combination, a support for a stack of blanks, a standard upon which the support is mounted, a carrier slideable upon the standard, walls mounted upon the carrier and ad-

justable thereon to provide for blanks of different sizes, and means for suspending the carrier from the top of the stack.

17. A device for use in locating the boards upon the covers of book cases having, in combination, a support for a stack of covers, walls for engaging the sides of the stack, gages for engaging edges of the boards, and a carrier upon which the gages and the walls are mounted, said carrier being movable in a path substantially perpendicular to the plane of the support.

18. A device of the class described having in combination, a support for a stack of blanks, a wall for engaging a side of the stack, means for suspending the wall from the top of the stack whereby the wall moves down as blanks are removed from the top of the stack, and operator-controlled means for raising the wall.

In testimony whereof I have signed my name to this specification.

FRED SEAMAN SHERMAN.
